UNITED STATES PATENT OFFICE.

CHARLES J. HENSCHEL, OF BLOOMFIELD, NEW JERSEY.

REMOTE CONTROL SYSTEM.

1,223,169.

Specification of Letters Patent. Patented Apr. 17, 1917.

Application filed March 9, 1914. Serial No. 823,367.

To all whom it may concern:

Be it known that I, CHARLES J. HENSCHEL, a citizen of the United States, residing at Bloomfield, in the county of Essex and State 5 of New Jersey, have invented certain new and useful Improvements in Remote Control Systems, of which the following is a specification.

My invention relates to remote control systems of the type in which an operator, located at one station, may exercise positive and accurate control over movable mechanism located at another station.

More particularly stated, my invention 15 relates to remote control systems, of the type just mentioned, and used mainly for purposes of signaling, but which may in some instances be employed with advantage in various other relations.

20 By my invention I seek to accomplish the following desirable results:

I. To reduce to a minimum the danger of failure of the system to cause a proper indication to be made at the receiving station 25 when such signal is impressed at the transmitting station.

II. To prevent any signal being given by the receiving station unless such signal is one properly impressed at the transmitting 30 station.

III. To prevent any indication from being made at the receiving station unless certain movable parts, interdependently associated with the signaling mechanism, are 35 actuated in connection with the transmission of the indication or signal.

IV. To enable a large number of distinct indications to be made by use of a relatively small number of electric circuits employed 40 for the purpose.

V. To insure the prompt and positive stoppage of certain movable parts used for displaying the signals transmitted.

VI. To facilitate the reading of the indications, by displaying the same upon a dial mechanism provided with display legends, and so arranged and operated as to avoid undue crowding of said legends when capable of making a large number of indications.

VII. To so arrange the circuits used for signaling that two distinct parts of each circuit are separately subjected to selectivity, so that no indication is made at the receiving station unless both parts of the circuit affected act in unison.

VIII. To enable the system to automati-

cally display a steady light when an indication, independent of said light, is given, and to automatically display a flickering light when certain troubles occur and said indication is not given.

IX. To control the circuits from the transmitting station through a plurality of signal wires, and to control the return of these circuits by selectively establishing a return path through some one of a number of return wires, whereby each signal wire may make as many selective indications as there are return wires.

As my invention may be practised in a large number of different ways, I do not deem it necessary to explain the many different forms of apparatus which could be employed in this relation. I will, therefore, illustrate and describe only a single representative form of my invention, to wit, a signaling system used, in this instance, as a ship's telegraph and comprising a transmitting station, which may be located upon the bridge of the ship, and a receiving station which may be in the engine room.

Reference is made to the accompanying drawing forming a part of this specification, and in which like letters indicate like parts.

Figure 1 is a general view, partly diagrammatic and partly in front elevation with certain parts broken away, and showing my system complete.

Fig. 2 is a section on the line 2—2 of Fig. 1, looking in the direction of the arrow.

I will first describe the mechanism of the receiving station.

A casing 1 contains the mechanism used at the receiving station, which in this instance I will suppose is located in the engine room of a battle ship. This casing has a lid 2, which is provided with peep holes or windows 3, 4, in this instance two in number. The casing 1 extends vertically, and at its bottom is provided with a guiding sleeve 5. Another guiding sleeve 6, carried by the casing, is located directly over the sleeve 5.

Secured within the casing are a number of supports 7, having in this instance the form of miniature brackets, and secured upon these brackets is a switch plate 8. Mounted upon the switch plate 8 is a stub shaft 8^a, and revolvably supported by this stub shaft is a sleeve 9. A display disk 10, a sprocket wheel 11 and a pulley 12 are mounted rigidly upon the sleeve 9, and revolvable therewith.

The display disk 10 carries a U-shaped

conductor 13 and a pair of contact members 14, 15 secured to the ends of this conductor, the contact members and conductor together constituting a contactor. Another conductor 16 and pair of contact members 17, 18, carried by the disk in question, together constitute another contactor.

A number of slip rings 19, 20, corresponding to the number of contactors, are mounted upon the switch plate 8. In this instance there are only two of these slip rings but the number of slip rings and contactors may be increased, if desired, in order to multiply the number of indications which may be transmitted.

Three stationary contact members 21, 22 and 23, are carried by the switch plate 8 and are spaced equidistant, as indicated in Fig. 1.

A sprocket chain 24 engages the sprocket wheel 11, and also engages another sprocket wheel 25, which has half the diameter of the sprocket wheel 11, and is located upon a revolute shaft 27. This shaft carries a display disk 26, which is provided with display legends as shown, the legends in this instance being merely the numbers 1, 2, 3.

The display disk 10 is likewise provided with a number of legends, in this instance six, namely, A, A, A, B, B, B. The legends A, A, A may here be interpreted to the effect that the engines are to proceed ahead, the legends B, B, B may indicate that the engines are to back, and the three numbers carried by the disk 26 may mean three different conditions or degrees of speed, for instance slow, normal and fast.

Located within the casing 1 is a shutter 28, and above this shutter are two windings 29, 30 together constituting a doubly-wound 40 solenoid.

A sliding rod 31, having its upper end of soft iron so as to serve as an armature for the solenoid, is slidably mounted in the sleeves 5, 6; and is adapted to be drawn upwardly when either winding of the solenoid is energized. The sliding rod 31 carries a contactor 32, which is insulated from it by an insulating washer 33. Two stationary contact members 34, 35 are so located as to be simultaneously engaged by the contactor 32, so as to support the sliding rod 31 when the latter is in its lowermost position.

Mounted rigidly upon the sliding rod 31 is an arm 36, carrying a pawl 37 and a small 55 idle pulley 38. Engaging this pulley is a belt 39, having in this instance the form of a flexible cable, and engaging a pulley 40. This pulley is carried by an electric motor 41 whereby it is actuated. The pulley 40, upon the motor 41, is very small, so that the display disks which are connected to the large pulley 12, rotate very slowly as compared to the speed of rotation of the motor 40, as it would be objectionable to have a 65 display disk rotate rapidly and acquire a

momentum, for it is necessary for the disks to be brought to rest promptly and accurately.

The display disk 10 is provided with notches 37^a located upon its periphery, and in this instance six in number, corresponding to the number of legends A, A, A, B, B, B. Whenever the sliding rod 31 is drawn upwardly, the pawl 37 engages the display disk 10, and passes directly into one of the notches 37^a. As this occurs, the idle pulley 38, being lifted by the sliding rod 31, relaxes the tension of the belt 39, so that the motor 41 can have no effect upon any other movable parts which it normally drives.

I will now explain the mechanism at the transmitting station, as indicated in the lower portion of Fig. 1.

A pair of mains are shown at 42 and 43. Connected with the main 43 is a wire 44, which runs to a pilot lamp 45. A short wire 46 extends from this pilot lamp to a stationary contact sector 47. A switch arm 48 extends across this sector and carries two contact bridges 49, 50. This switch arm is provided with a handle 51 whereby it may be actuated. Disposed adjacent the sector 47 are a number of stationary contact members 52, 53, 54, 55, 56 and 57. A number of other stationary contact members are shown at 58, 59, 60, 61, 62, and 63. Two wires 64, 65 are connected together and are also connected with the stationary contact members 52, 54 and 56. Another wire 66 is connected to the contact member 53 and to a wire 67, the latter leading to the contact members 55 and 57. A wire 69 leads from the contact member 58 to the contact member 59. A wire 70 connects together the contact members 60 and 63.

A wire 71 is connected with the contact member 56 and leads therefrom to the solenoid winding 29. Another wire 72 leads from the contact member 57 to the solenoid winding 30.

Connected with the contact member 63 is a wire 73, which leads to the stationary contact member 23, supported by the switch plate 8. Similarly two wires 74, 75, connected respectively with the contact members 58 and 61, lead therefrom to the contact members 21, 22 respectively. A wire 76 is connected with the wire 44 and the main 43 and leads to the contact member 35. A wire 77 is connected with a pilot lamp 78, and leads therefrom to the motor 41. The pilot lamp 78 is connected by a wire 79 with the main 42 and with a wire 80, this wire leading to a contact sector 81. A wire 82 leads from the motor 41 to the contact member 34. A wire 83 extends from the contact member 61 to the contact member 62. Wires 84, 85 lead from the respective windings 30, 29 to the respective slip rings 19, 20.

Whenever the signaling system is inactive

or idle, the switch handle 48 occupies its middle position, as indicated in Fig. 1; the solenoid windings 29 and 30 are deenergized, and the sliding rod 31 occupies its lowermost position. The shutter 28 is down, and obscures the windows 3 and 4; the pilot lamp 45 makes no light; the motor 41 is in action, and the pilot lamp 78 burns steadily; the display disks 10 and 26 are rotating, but 10 invisible because hidden by the shutter 28; the rotation of the display disk 26 is in a clockwise direction, and the rotation of the display disk 10 is also in a clockwise direction, according to Fig. 1.

15 If for any reason, the motor circuit becomes accidentally broken or inoperative, the pilot lamp 78 will disclose the existence of the trouble.

The motor circuit is always closed except 20 when an indication is made or when something is wrong, and may be traced as follows:

Main 43, wire 76, contact members 35, 32, 25 34, wire 82, motor 41, wire 77, pilot lamp 78, wire 79, main 42 to source of electricity (not shown); thence back to main 43.

The operation of my device is as follows:

I will suppose that the system is in its idle condition as just described, and that the 30 operator at the transmitting station wishes to apprise the operator at the receiving station to the effect that the engine is to go ahead, at the slowest of its three conventional speeds. The legends for making this 35 indication are the numeral 1, carried by the disk 26 and referring to speed, and one of the letters A, carried by the disk 10, and referring to direction. The operator at the transmitting station grasps the handle 51 40 and swings the switch arm 48 slightly to the right, so that the contact bridge 49 engages stationary contact member 54, and the contact bridge 50 extends from the contact sector 81 to the stationary contact member 60.

As the disks 10 and 26 are turning, as above described, the contact members 15 and 18 carried by the disk 10 are sliding around upon the slip rings 19 and 20, and the contact members 14 and 17 each intermittently engage the several stationary contact members 21, 22 and 23. As soon as the movable contact member 14 engages the stationary contact member 23, or in other words, as 55 soon as a wiping contact is made between these two contact members, the following circuit is completed:

Main 43, wire 44, pilot lamp 45, wire 46, sector 47, bridge 49, contact member 54, wire 60 65, wire 71, winding 29, wire 85, slip ring 19, movable contact member 15, conductor 13, movable contact member 14, stationary contact member 23, wire 73, contact member 63, wire 70, contact member 60, bridge 50, 65 sector 81, wire 80, main 42 to source of elec-

tricity (not shown), thence back to main 43. This circuit thereupon energizes the winding 29 and the pilot lamp 45, so that the sliding rod 6 is raised and the pilot lamp 45 gives a steady light, which continues 70 until the sliding rod 31 is lowered by the opening of the circuit through the solenoid, as controlled by the transmitting station.

The operator at the transmitting station by observing the pilot lamp 45, is apprised 75 that the signaling circuit through the winding 29 is in good order, and consequently that a signal is being displayed at the receiving station.

As the sliding rod 31 moves upwardly, 80 carrying with it the shutter 28, the windows 3 and 4 are uncovered, and the operator at the receiving station can observe the legends upon the display disks 26 and 10. The upward movement of the sliding rod 31 lifts 85 the bridge 32 out of engagement with the stationary contact members 34 and 35. This opens the motor circuit, and allows the motor to slow down and stop, which, however, may require some little time—say, half 90 a minute. The lifting of the sliding rod 31, carrying with it the arm 36, causes the idle pulley 38 to relax its pressure upon the belt 39, and in doing this virtually disconnects the motor 41 from the display disks 10 and 95 26. At the same time this occurs, the pawl 37 is brought into engagement with the display disk 10, and slips directly into the proper one of the notches 37^a. This abruptly stops the rotation of both disks 10 100 and 26.

The operator at the transmitting station knows, from observing a steady light given off from the pilot lamp 45, that a signal is being properly displayed. He also knows, 105 from the darkness of the lamp 78, that the motor circuit is now broken.

The disk 10 being now stationary, the conductor 13 maintains the slip ring 19 constantly in circuit with the stationary contact member 23, so that the solenoid winding 29 remains energized, and the sliding rod 31 is supported in its uppermost position so long as the switch arm 48 remains in the position into which it has been shifted. 115 Consequently the signal thus displayed at the receiving station remains visible to the operator at the station last mentioned, until the switch arm 48 is moved into some other position.

Suppose, now, that the operator at the transmitting station wishes to transmit the signal 2^A. To do this, he shifts the switch arm 48 still farther to the right, that is, so that the bridges 49, 50 are respectively 125 brought into engagement with the contact members 53 and 59. This movement of the switch arm 48, breaks the previously described circuits through the solenoid winding 29, which releases the sliding rod 31, 130

and lets it drop, thus releasing the pawl 37, from engagement with the disk 10, and starting the motor 41, and tightening the belt 39, so that the disk 10, commences to 5 rotate, and when the movable contact 17, makes a wiping contact with the stationary contact 21, the solenoid is energized and the motor and display disks brought to rest again as the following circuits are estab- 10 lished:

Main 43, wire 44, pilot lamp 45, wire 46, sector 47, bridge 49, contact member 53, wires 66, 67, contact member 57, wire 72, solenoid winding 30, wire 84; slip ring 20, movable contact member 18, conductor 16, 15 movable contact member 17, stationary contact member 21, wire 74, contact member 58, wire 69, contact member 59, bridge 50, sector 81, wire 80, main 42 to source of electricity, 20 thence back to main 43. This causes the disk 10 to stop in such position that the movable contact member 17, carried by it, is in engagement with the stationary contact member 21, the disk in question thus displaying the legend A. The disk 26 is 25 stopped in such position as to display the legend 2. The complete indication, therefore, is 2^A, which means that the engine is to be driven ahead at its normal or intermediate speed. The pilot lamps and various other parts act as above described, the operator at the transmitting station being thus duly apprised that the signal has been displayed.

35 Similarly the operator at the transmitting station, in order to transmit the signal 3^A, which means that the engine is to go ahead at maximum speed, shifts the switch arm 48 still farther to the right, so as to bring 40 the bridges 49, 50 into engagement with the contact members 52 and 58. The following circuit is thus completed:

Main 43, wire 44, pilot lamp 45, wire 46, sector 47, bridge 49, contact member 52, 45 wires 64, 65, wire 71, winding 29, wire 85, slip ring 19, movable contact member 15, conductor 18, movable contact member 14, stationary contact member 21, wire 74, contact member 58, bridge 50, sector 81, wire 50 80, main 42 to source of electricity, thence back to main 43. This causes a cycle of movements to take place substantially as above described, the display disk 10 being stopped in such position as to display a 55 legend A, the display disk 26 being stopped in such position as to display the legend consisting of the numeral 3. The total indication therefore is 3^A.

Suppose, now, that the operator at the 60 transmitting station wishes to transmit a signal to the effect that the engine is to back at its minimum speed. He shifts the switch arm 48 to the left of its normal position according to Fig. 1, so that the bridges 49, 50 engage the contact members 55 and 61.

The following circuit is thus completed: Main 43, wire 44, pilot lamp 45, wire 46, sector 47, bridge 49, contact member 55, wire 67, contact member 57, wire 72, solenoid winding 30, wire 84; slip ring 20, movable contact member 18, conductor 16, movable contact member 17, stationary contact member 22 (now engaged by the latter), wire 75, contact member 61, bridge 50, sector 81, wire 80, main 42 to source of electricity, 75 thence back to main 43.

The operations above described with reference to other signaling circuits traced are now substantially repeated, the indication displayed, however, being 1^B.

In order to indicate that the engine is to back at normal or intermediate speed, 2^B, the operator shifts the signal arm 48 still farther to the left, so that the bridges 49, 50 engage the contact members 56, 62.

The following circuit is thus completed:

Main 43, wire 44, pilot lamp 45, wire 46, sector 47, contact member 56, wire 71, solenoid winding 29, wire 85, slip ring 19, movable contact member 15, conductor 13, movable contact member 14, stationary contact member 22, wire 75, contact member 61, wire 83, contact member 62, bridge 50, sector 81, wire 80, main 42 to source of electricity, thence back to main 43. The apparatus now 95 makes the indication last mentioned.

Suppose that the switch arm 48 be moved still farther to the left, so that the bridges 49, 50 are brought into engagement with the contact members 57, 63.

The following circuit is thus completed: Main 43, wire 44, pilot lamp 45, wire 46, sector 47, bridge 49, contact member 57, wire 72, solenoid winding 30, wire 84, slip ring 20, movable contact member 18, conductor 16, movable contact member 17, stationary contact member 23, wire 73, contact member 63, bridge 50, sector 81, wire 80, main 42 to source of electricity, thence back to main 43. This circuit causes the various steps to take 110 place substantially as above described, the disks 26 and 10 being stopped in such positions as to display the legends 3^B.

When the proper signal has been displayed in the engine room, the pilot lamp 45 115 burns steadily and the pilot lamp 78 is dark.

Suppose, next, that during the operation of the system the solenoid fails to lift the sliding rod 31 from its normal position, in this event the motor circuit remains closed 120 and the pilot lamp 78 so indicates. If the motor is turning the disk 10, and the pawl fails to stop it, and the wiping contacts periodically makes a circuit established through the lamp 45, it flickers, thus indicating the exact fault.

Suppose the pilot lamp 45 burns steadily on one indication at the sending station but fails to burn when another legend should be displayed; then either the motor does not 130

run properly or the pawl 37 has locked the rotating disks, or they are stuck and only one correct, but no incorrect signal can be displayed without the knowledge of the transmitting operator.

If both pilot lamps burn steadily at the same time, a fault is indicated at the transmitting station.

It will be noted that the mechanism at the transmitting station, in controlling the circuits leading to the receiving station, is selective in two relations. That is to say, the transmitting switch acts selectively upon portions of the circuit leading from the transmitting switch to the receiving station, and also acts selectively upon the so-called return paths along which the current flows. By this arrangement, each wire used for signaling can make as many selective indications as there are return wires. The number of indications possible for a given number of signal wires is thus greatly increased.

As may be understood from the foregoing description, my system admits of reliable and efficient construction embodying a minimum liability to give false signals, and well adapted to indicate, at distances remote from the receiving station, that the indication has been properly made.

It will also be noted that if for any reason there is a failure in the action of any electric circuit, or in the proper functioning of any mechanical part, no indication at all is made, or else the operator at the transmitting station is duly apprised of the existence of a fault.

This is upon the well known principle that a false indication is far worse than no indication, and that the failure of an indication is worse if unknown than if known, to the transmitting operator.

I do not limit myself to the precise construction shown as variations may be made therein without departing from the spirit of my invention.

Neither do I limit myself to any particular use which may be made of my invention.

Having thus described my invention, what I claim as new and desire to secure by Letters Patent is as follows:

1. A remote control system comprising a movable and several stationary contact members, a motor to continuously move the movable contact member into successive contact with said stationary contact members, successive control circuits through the movable and stationary contact members and electro magnetic means to stop the movement at a predetermined position by energizing any one of said circuits.

2. A remote control signaling system comprising a signal member, a plurality of controlling circuits for said signal member, a normally continuously driven motor, contact mechanism driven by said motor for open-

ing and closing said circuits successively in order to cause said signal to display successive indications, and mechanism remote from said motor for stopping the latter at any predetermined one of said indications. 70

3. In a remote control signaling system, the combination of a signal member, a motor for normally actuating the same continuously, a plurality of electric circuits, contact mechanism connected with said circuits for opening and closing the same, said contact mechanism being normally actuated by said motor, and means controllable by said circuits and said contact mechanism for stopping said motor when said signal member indicates a predetermined signal. 80

4. A remote control signaling system comprising a signal member, non-reversing mechanism for actuating the same, a plurality of electric circuits each connected with said mechanism and selectively adapted to control the same, and a shutter to normally obscure said indicating member and means connected with said circuits and mechanism to open the shutter at predetermined intervals. 85

5. A remote control system comprising a movable indicating member, means for actuating the same continuously in one direction, mechanism controllable from the transmitting station for stopping said indicating member in a predetermined position, and a shutter also controllable from the transmitting station for preventing any indication except the proper one. 95

6. In a remote control system the combination of an indicating mechanism, a motor for continuously actuating the same in one direction, and selective mechanism connected with said indicating mechanism and with said motor, and controllable at a distance therefrom, for stopping said motor and disconnecting said motor from said indicating mechanism. 105

7. In a remote control system, the combination of an indicating mechanism, a motor for actuating the same continuously in one direction in order to bring said indicating mechanism into successive positions for making different indications, shutter mechanism for normally preventing said indicating mechanism from being observed, and selective mechanism controllable at a distance from said indicating mechanism, for stopping said indicating mechanism and removing said shutter mechanism. 110

8. In a remote control system, the combination of a plurality of revoluble display members geared together and each provided with legends, means for normally turning said revoluble display members in order to form successive groups of legends, shutter mechanism disposed adjacent said display members in order to normally hide said groups of legends as formed, and mechanism 125

common to said revolute display members and said shutter mechanism and controllable selectively from a distance for stopping said revolute display members in predetermined relative positions, and actuating said shutter mechanism so as to display a predetermined group of legends.

9. In a remote control system, the combination of a revolute display member provided with intelligible characters, a motor for turning said revolute display member, a second revolute display member geared to said first mentioned revolute display member and provided likewise with intelligible characters, said second-mentioned display member having a speed of rotation greater than said first-mentioned

display member in order to increase the number of groups of intelligible characters capable of being displayed by both display members acting conjointly, motor mechanism for turning said display members, and means controllable at a distance from said display members for selectively stopping said display members, in predetermined relative position.

In testimony whereof I have signed my name to this specification in the presence of two subscribing witnesses.

CHARLES J. HENSCHEL.
